Specification for Design.

Patented Apr. 18, 1916.

Application filed February 17, 1916. Serial No. 78,997. Term of patent 3½ years.

To all whom it may concern:

Be it known that I, ARTHUR STUART JOHNSON, a subject of the King of Great Britain and Ireland, residing at Congleton, Cheshire, England, have invented a new, original, and ornamental Design for a Covered Dish or Similar Article, of which the following is a specification, reference being had to the accompanying drawing, forming part thereof, in which—

plan view of a covered dish illustrating my new design.

I claim:

The ornamental design for a covered dish or similar article as shown.

In testimony whereof I affix my signature in presence of two witnesses.

ARTHUR STUART JOHNSON.

Witnesses:

R. O. DOBSON,
J. H. COPESTAKE.
